UNITED STATES PATENT OFFICE.

MAXIMILLIAN G. VOIGTLANDER, OF HARRISON, OHIO.

IGNITER FOR GAS AND GASOLENE ENGINES.

No. 878,694.

Specification of Letters Patent.

Patented Feb. 11, 1908.

Application filed August 8, 1906. Serial No. 329,648.

To all whom it may concern:

Be it known that I, MAXIMILLIAN G. VOIGTLANDER, a citizen of the United States, residing at Harrison, in the county of Hamilton and State of Ohio, have invented certain new and useful Improvements in Igniters for Gas and Gasoline Engines, of which the following is a specification.

My invention relates to improvements in igniters for gas and gasoline engines.

One of its objects is to provide a simple, reliable and efficient mechanism by means of which a match may be ignited within the explosion chamber by the operator to secure an initial explosion to start the engine.

Another object is to provide mechanism by means of which the ignition of the match is made certain, and by means of which the match may be readily and conveniently inserted and removed.

It further consists in certain details of form, combination, and arrangement, all of which will be more fully set forth in the description of the accompanying drawings, in which:

Figure 1 is a side elevation of my improved mechanism in position for use, being shown mounted in the cylinder head, which with part of the mechanism is shown in section. Fig. 2 is an end view of the mechanism looking at the end within the cylinder. Fig. 3 is a section on line *v v* of Fig. 1. Fig. 4 is a perspective view of the inner end of the match carrying plunger.

With larger sizes of gas and gasoline engines it is difficult to start the engines as is done with smaller engines by turning the flywheel by hand until an explosion occurs, and it is therefore desirable to start such machines by exploding an initial charge or mixture of air and explosive gas or vapor by hand operated mechanism, after which an electric igniter driven in conjunction with the engine will ignite the succeeding charges.

In the accompanying drawings A represents part of the wall of the explosion chamber of the cylinder, preferably the cylinder head, which is preferably provided with an outwardly projecting boss A' to receive the igniter. The igniter includes the following parts, a plug B having screw threaded engagement with the cylinder head A.

b represents the head of the plug which seats against the cylinder head and is preferably milled on its exterior so as to be readily screwed in and unscrewed by hand.

b' represents holes to receive a spanner wrench if necessary.

C represents a spiral groove in the inner reduced end of plug B, and D a lip or finger projecting inwardly from the inner end of the plug. The inner face *d* of finger D is provided with a roughened surface and is slightly eccentric to the axis of the plug as indicated in Fig. 2 and also tapers toward the axis of the plug at its outer end as shown in Fig. 1.

Mounted in the axial bore *b* of plug B is a plunger E having an offset *e* normally seating against a corresponding offset *b* in the bore *b*. These offsets serve to prevent the plunger E being forced through the plug B by pressure from within the cylinder, and also form a close joint or valve to prevent the escape of gases from the cylinder at this point.

F represents a spring outside the cylinder head to retain the plunger normally in the retracted position, and G a knob or knurl pivotally connected to the outer end of plunger E by means of set screw *g* entering an annular recess *e* in the end of plunger E.

The inner end of plunger E is preferably slit at *k* as indicated in Fig. 4 and is provided with a recess *h* to receive the stem *h'* of an ordinary match, preferably of the kind known as "parlor match". The head *i'* of the match projects at one side of the plunger as indicated in Figs. 1 and 2, while the excess of match stem at the opposite side of the plunger is broken away. The slit *k* causes the match stem to be yieldingly clamped in the end of plunger E, and facilitates the removal of the match stem after it has been ignited. A pin L carried by the plunger E slides in the slot C and causes the plunger E to partially rotate when pressed inward by means of knurl G.

In operation, when it is desired to start the engine, the plug B is first unscrewed and removed from the cylinder head, a match is inserted in recess *h*, the excess match stem broken away, and the plug again screwed tightly into place in the cylinder head. The gas or gasoline valve is then opened and the engine turned or adjusted to take in an explosive charge and to the position ready for the explosion of such initial charge. The knurl G is then struck a sharp blow with the hand, which serves to ignite the match head *i* by drawing the same in a spiral direction across the roughened inner face of finger D, thereby insuring the ignition of the match or

at least a spark sufficient to explode the charge in the cylinder. The initial explosion produces a sufficient number of revolutions of the engine to enable the electrical igniter 5 to explode successive charges and the engine continues to run as long as desired.

The mechanism herein specified is capable of considerable modification without departing from the principle of my invention.

10 Having described my invention, what I claim is;

1. In a mechanism of the character indicated, a plug detachably connected to the cylinder to permit the adjustment of a match 15 to place when detached, a segmental finger having a roughened surface, said finger being carried by said plug and projecting into the cylinder gases, a plunger mounted in said plug, adapted to move endwise relative thereto, and provided at its inner end with means for holding a match at an angle to, and in position to contact with said roughened surface when the plunger is forced inward.

2. In a mechanism of the character indicated, a plug connected to the cylinder and adapted to be detached to adjust a match to place, a finger carried by said plug having an inclined roughened surface in contact with the gases of the cylinder, a plunger mounted 30 in said plug adapted to move endwise relative thereto, and provided at its inner end with means for holding a match in position to contact with said inclined roughened surface when the plunger is forced inward, a spring 35 mounted on said plunger outside the plug to normally hold the plunger retracted, and a knurl pivotally attached to the outer end of said plunger.

3. In a mechanism of the character indicated, a detachable plug having threaded engagement with the cylinder, a finger projecting from said plug in contact with the cylinder gases and provided with a roughened

surface, a plunger mounted in said plug adapted to move endwise relative thereto, and 45 provided at its inner end with means for holding a match in position to contact with said roughened surface when the plunger is forced inward, and interengaging surfaces carried by said plug and plunger to partially rotate 50 said plunger when forced inward.

4. In a mechanism of the character indicated, a plug connected to the cylinder and adapted to be detached to adjust a match to place, a projecting finger having an inclined 55 roughened surface, said finger being carried by said plug and in contact with the gases of the cylinder, a plunger mounted in said plug adapted to move endwise relative thereto, and provided at its inner end with means for 60 holding a match in position to contact with said inclined roughened surface when the plunger is forced inward, and engaging offsets carried by said plug and plunger to prevent the plunger being forced outward by 65 pressure within the cylinder.

5. In a mechanism of the character indicated, a plug detachably connected to the cylinder, a finger having an inclined roughened surface in contact with the cylinder 70 gases, a plunger mounted in said plug adapted to move endwise relative thereto, and provided at its inner end with means for holding a match in position to contact with said inclined roughened surface when the plunger is 75 forced inward, a spring to normally hold the plunger in the retracted position and means for holding the plunger in place against the pressure from within the cylinder, and the escape of gases between the plunger and plug. 80

In testimony whereof I have affixed my signature in presence of two witnesses.

MAXIMILLIAN G. VOIGTLANDER.
